UNITED STATES PATENT OFFICE.

JOHN B. SEMPLE, OF SEWICKLEY, PENNSYLVANIA.

PROJECTILE.

1,172,637.

Specification of Letters Patent. Patented Feb. 22, 1916.

Application filed February 3, 1915. Serial No. 5,886.

To all whom it may concern:

Be it known that I, JOHN B. SEMPLE, residing at Sewickley, in the county of Allegheny and State of Pennsylvania, a citizen 5 of the United States, have invented or discovered certain new and useful Improvements in Projectiles, of which improvement the following is a specification.

My invention relates to an improvement 10 in projectiles.

It is illustrated in the accompanying drawings, in which—

Figure 1 is a view in longitudinal central section of the posterior end of a projectile 15 in which my present invention is embodied; Fig. 2 is a view in cross section of the fuse stock of the projectile of Fig. 1, the plane of section being indicated by the line II—II, Fig. 1; and Fig. 3 is a view in cross section 20 illustrating a detail of construction, the plane of section being indicated by the line III—III, Fig. 1.

In a co-pending application, Serial No. 835,131, filed April 29, 1914, and allowed 25 August 5, 1914, I have described and claimed a projectile including in its structure a movable member controlling detonation, a member which, when in normal inoperative position, does not afford the im- 30 partation of detonation from detonator to burster charge, but which, when under the conditions of firing it has moved from its normal inoperative position to operative position, establishes detonation communica- 35 tion from detonator to burster charge. In that application I have shown and described and specifically claimed one specific arrangement of such instrumentalities as I have just indicated.

40 In a second co-pending application, filed January 29, 1915, Serial No. 5022, I have shown another specific form of such means. In this application I show and describe still another specific means of the nature indi- 45 cated.

Detonation is a phenomenon exhibited by certain substances termed "high explosives". It is a sudden, substantially instantaneous, and tremendously powerful breaking down 50 of the whole body, and is many times more powerful than the explosion of an equal amount of black powder. Detonation is im- parted not by physical transfer of matter, like a flash traversing a duct; it is an im- 55 pulse, and is transmitted like electricity through a suitable conductor; it will not

traverse wide air gaps. (Under conditions such as obtain in my work it will not leap a gap in a transmitting conductor which is wider than the diameter of the conductor.) 60

Some high explosives are very inert to ordinary shocks and though combustible and even capable of low-power explosion on ignition, do not on ignition manifest that high-power explosion called detonation. 65 That phenomenon is produced in them only on and by detonation of an adjacent body of high explosive. There are other high explosives which are exceedingly sensitive, and detonate on ignition. 70

The high explosives of the class first mentioned are, by reason of their insensitivity, well adapted to use for the burster charges of explosive projectiles; the problem attending their use being how to effect 75 their detonation at the proper time. The high explosives of the second class, though unsuitable because of their extreme sensitivity to be used in relatively large masses as burster charges for projectiles, are well 80 suited to be used in small masses and in intermediate position between the percussion cap of an explosive projectile and the burster charge of inert high explosive, to be detonated on the flash of the cap and to im- 85 part detonation to the burster charge. In such an arrangement the problem is to safeguard the burster charge against detonation in case of accidental and premature detonation of the intermediate charge (commonly 90 called the "detonator"). Various expedients in the prior art involve the use of detonators which are movable from remote and innocuous to proximate and detonation-imparting position adjacent the burster charge. 95 My application first referred to (Serial No. 835,131, now Patent No. 1,131,164) involves such an arrangement.

The invention of my application Serial No. 5022, is directed to the use of a stationary detonator together with suitable control of a path of detonation transmission from detonator to burster charge. My present invention is a further improvement in that same arrangement. 100

In this case, as in the case second mentioned above, B is the booster charge which, as in those other cases, I shall simply consider as part of the burster charge.

D is the detonator arranged within its 110 safety chamber 14, and in this case having no normal motion of translation. The

burster charge B and the detonator D are separated from one another by heavy walls which, but for the path of detonation transmission, (which may be made or broken), is effective to preserve the burster charge B safe from detonation in case of the premature explosion of the detonator D. The safety chamber 14 is provided to receive the gases of explosion and relieve the intensity 10 of the stresses incident to a premature detonation of detonator D.

Through the heavy wall alluded to, which normally separates the burster charge B and the detonator D, extends a column 13 of detonation-transmitting material, the continuity of which column is normally interrupted by a space in which move two complementary bolts 6—6. These two bolts 6 are movable under stress or strain incident 15 to the firing and flight of a projectile from a gun as, for example, conveniently by centrifugal force exerted upon them by the rotation of the projectile, and to this end the space in which they move is a runway 20 which is more or less exactly radial. The members themselves are provided each with a column of detonation-transmitting material and the members 6 themselves are spring-backed as indicated, the springs normally holding the members 6 in position 25 shown in Fig. 1.

When the parts are in the position shown in Fig. 1 it will be observed of columns 12 of detonation-transmitting material with 30 which the two bolts are provided, that they are remote one from another and from the main column 13; and it will be understood that when in the flight of the projectile from a rifled gun these bolts slide outward each 35 against the tension of its backing spring, these two columns 12 will be brought into register one with another and with the main column 13, to form a continuous path of detonation transmission from detonator to 40 burster charge. A plurality of these members is provided to this end: In case of a jar or shock accidentally imparted to the projectile when assembled, coinciding or 45 substantially coinciding with the direction of possible movement of one of these members, the member may yield aside, and so be accidentally shifted to detonation-transmitting or armed position. With two members yielding in different directions, no shock 50 can arm them both at once and so, by the provision of two, a secure provision is made 55 against accidental arming.

With these general and prefatory explanations, it will be understood that the runway 60 3 in which the members 6 are movable will preferably be a single runway extending diametrically across the center of rotation of the projectile, and that the members 6 are so weighted that their centers of gravity 65 lie on opposite sides of the center of ro-

tation. Means are provided for holding the two members 6 when once they have been brought to operative or armed position against retraction. Any preferred locking means may be employed. I have found it 70 well to provide a spring-backed lock 7 lying in a recess in one of the contacting faces upon which the two members 6 move, one with respect to the other, and in providing in the other and complementary member a 75 recess 15 into which the locking block 7 under spring pressure will be thrown when the recess 16 comes into register with it, which will be when the two members 6 have moved to armed position, and their pathways 12 80 alined with and forming part of detonation pathway 13.

With this explanation the operation will be fully understood.

When the parts are in the unarmed position shown in Fig. 1, no shock communicated in any direction will be effective to throw both of the moving members 6 to armed position. So that always prior to firing the path of detonation transmission 90 will be interrupted by at least one member, and in case of premature explosion of detonator D the burster charge B cannot be detonated. When however the projectile has been fired from a rifled gun, both members 6 will move outward, the springs which normally hold them to inoperative position yielding, the two columns 12 will be brought to register with one another and also to register with the column 13, and when the two 100 blocks have moved until their columns 12 are so in registry, then the two members will be locked by the lock 7. Thereafter, when in the regular manner detonator D is fired, detonation will be imparted through 105 the continuous pathway 13—13, 12—12, to the burster charge B.

As explained in the second of my pending applications mentioned above, the pathway 110 13, and the pathways 12, in the movable parts 6 will be formed of detonation transmitting material such, for example, as tri-nitro-toluene.

I claim as my invention:

1. In an explosive projectile the combination of a burster charge, a detonator, a path of detonation transmission extending between said detonator and said burster charge, a plurality of detonation controlling members movable in different directions in a break in said path from positions in which the path is interrupted to positions in which the path is continuous.

2. In an explosive projectile the combination of a burster charge, a detonator, and a path of detonation transmission from said detonator to said burster charge, a pair of oppositely movable centrifugal bolts arranged in a break in said path, each of said bolts provided with a supplementary path 130

of detonation transmission, the movement of said bolts permitting the alinement of such supplementary paths with one another and with the main path, and a locking means 5 automatically securing said bolts against reverse movement when once they have in their movement brought all the said paths into alinement.

3. In an explosive projectile the combination of a burster charge, a detonator, and a 10 path of detonation transmission from said detonator to said burster charge, a pair of overlapping spring-impelled and centrifugally receding bolts arranged in a break in 15 said path and in the range of their movement establishing the continuity of said path across such break, and interlocking means arranged in the overlapping faces of 20 said bolts.

20 4. In an explosive projectile the combination of a burster charge and a detonator arranged on opposite sides of a dividing wall, a bore extending through said wall, a second bore crossing the bore first named and extending transversely to and on either side 25 of the axis of rotation of the projectile as a whole, a pair of centrifugal bolts movable in the second named bore, a bore in each of said bolts, and columns of detonation-trans- 30 mitting material filling the bore first named and filling the bores in the said pair of bolts.

5. In an explosive projectile the combination of a burster charge, a detonator, a wall separating said detonator from said burster charge, a pair of oppositely movable overlapping centrifugal bolts arranged in a runway formed in said wall, and a detonation path formed in said wall from said detonator to said burster charge and made continuous through said bolts when moved oppositely under centrifugal force. 35

6. In an explosive projectile a burster charge of high explosive arranged within the projectile and in its shape consisting of a larger main body and an attenuated extension, and, in combination with a burster charge so shaped, a detonator arranged at the remote end of said extension, and a make-and-break device arranged in said extension of the burster charge, such make-and-break device including a plurality of parts movable each in a different direction from a position of interruption to a position in which the continuity of the said extension of the burster charge is established 50 through it. 55

In testimony whereof I have hereunto set my hand.

JOHN B. SEMPLE.
